UNITED STATES PATENT OFFICE.

WILLIAM E. BEATTY, OF CINCINNATI, OHIO.

SODA-FOUNTAIN AND ICE-CREAM SERVICE OR DISPENSING APPARATUS.

Application filed October 20, 1924. Serial No. 744,826.

- This invention relates to combination soda-fountain and ice-cream service-apparatus, taking into consideration at the same time that either service-apparatus is adapted 5 for use independent of the other and in separate locations remote from each other if need be or desired.
- The invention relates, however, more particularly to the ice-cream dispensing-cabinet taken by itself regardless, in most instances, of any soda-fountain or other liquid refreshment service-apparatus.
- The prime object of the essential feature herein is to provide an ice-cream serving-cabinet with an internal turn-table on which a multiplicity of ice-cream containers or cans are mounted whereby one or more of the cans can be brought to the front to the actual 10 point of service for the better convenience of the attendant in facilitating the removal of the contents of the cans in portions to suit the piecemeal demands of the consumers thereof, and without undue reaching or stretching, or any unnecessary leaning forward to accomplish such purpose. The said turn-table support further enables the ready removal and replacing of cans from and into the cabinet, and without removing its covering or closing top.
- Another important object of the invention is to provide a lid that slides horizontally into a concealing receiver-pocket structure for the cabinet and that enables the use of the cans without any lids on them directly and, 15 also, to further provide a dry air and insulator structure for the cabinet top-lids and the walls that prevents sweating or condensation within the ice-cream chamber that would otherwise drip into the cream, especially if no lids are used directly on the cans themselves.
- Still another important object of the invention is to provide means, through the use of said turn-table support for the cans, 20 of imparting a rotary movement that causes a circulation of the brine within the cabinet and keeps it at a uniform refrigeration throughout to have a like effect on the frozen contents of all the cans.
- Still another object of a minor part of the invention herein is to provide an unobstructed slab or flat top to the rear half of the cabinet for very material use in displaying goods connected with the business where the cream is sold or dispensed, or in arranging and holding dishes, tableware, cakes, 25 nuts and the like in the ice-cream or other frozen-mixture service.
- Still another quite material advantage or object of my invention herein is to dispense 60 with the use of ice and otherwise solely provide mechanical-refrigeration means to maintain the hardened or frozen contents of the cans within the cabinet that contains a brine that surrounds the can-encompassing 65 jackets, the latter, in turn, being mounted on the aforesaid turn-tables or rotatory-bases for the said uniform circulatory effects and to enable the many different kinds of frozen can-contents to be brought to the 70 front at a single point for the said desired convenient and comfortable dispensing service.
- Other features of the invention will be fully described in connection with the said 75 more important ones on reference to the accompanying sheet of drawings, in which—
- Figure 1 is an open, perspective view showing one end of the cabinet in cross-section and the other end broken off at the 80 middle portion of the device, which is a double-service one and with two of the jacketed-cans omitted, and the view otherwise showing the usual coil used in the chambers, at the said center of the device, 85 for imparting the freezing cold-retaining medium to the brine contents of the cabinet; Fig. 2, a detail cross-section of a fragmentary part of the central portion of the turn-table mount and its pivot-box in the bottom 90 of the cabinet, such bottom of the cabinet being shown broken off, too, and in section; Fig. 3, a detail plan view of the said pivot-box for setting the turn-table in the said bottom of the cabinet, but with the bottom 95 and the turn-table omitted, a part only of the pivot-shaft being shown in this view; Fig. 4, a plan view of one rotatory-service end of my improved cabinet when made double and with the other rotatory-service 100 end broken off, as in Fig. 1, but showing the upper insulator filler-blocks between the can-jackets, and with but one of said jackets containing a can; Fig. 5, an end elevation, partly broken off and in section (taken on the dotted-line 5, 5 of Fig. 7), to more distinctly show or display the removable top of the cabinet and including its slidable covering-lid and the concealing receiver-pocket for such lid, and, also, showing the 105 adaptability of soda-fountain syrup containers to the rear half of the cabinet back of

the display-board referred to above, leaving room to the front of said syrup containers for holding glasses and the like used in the service of beverages and the ice-cream; Fig. 5 6, a cross-section of one of the closure-lids showing on its under surface the desired form herein of insulator-structure to obviate sweating of the said closure-lid within the cabinet chamber below; Fig. 7, a plan view 10 of the cabinet, showing it in double form and in combination with an array of soda-fountain syrup-containers that are intended for convenient use in connection with the ice-cream dispensers to the front of the device, this view further showing one of the 15 top closure-lids pushed back for access to the two forwardly-turned cream-containers and the other top closure-lid in its forward and closed position, over the dispenser-compartment, not being used simultaneously by the attendant; and Fig. 8, a perspective view of the cabinet taken as an entirety, but omitting the soda-fountain apparatus, however, and with one of its closure-lids shown open, 20 for access to the pair of ice-cream container-cans below or within.

9 and 10 indicate opposite longitudinal-walls of the cabinet having insulated hollow interiors 11; and 12 is the bottom of the 30 cabinet, of similar construction, with an insulated hollow interior 13 and an upper superposed hollow layer 14, as best seen in Fig. 1, such insulated structures being provided to preserve the freezing-cold within 35 the cabinet and, also, correspondingly prevent condensation or sweat on the outside of the cabinet. The top or cover 15 of the cabinet is of like insulated construction and has a pair of rectangular openings 16 and 17 40 therein for access to the contents of the cabinet that is divided centrally into two chambers by means of a vertical partition 18 so as to use the two chambers independently, if desired, especially when but one chamber 45 is required for the service that may vary during different seasons of the year. A coil 19 is mounted in the cabinet to convey the mechanically - propelled freezing - mixture into contact with the fluid brine-contents of 50 the cabinet for preserving the congealed and hardened condition of the cream in the cans 20 that are placed or inserted in the jackets 21 so as to be out of direct-contact with the brine that is placed in the cabinet up to 55 a level of about two inches (more or less) from the top of each of the said two chambers, whereby the full effect of the sustaining freezing-medium in the cabinet is utilized, from top to bottom of each can and its 60 compassing-jacket.

In Fig. 4, where I show but one of the ice-cream chambers, the other one (to the left) of the two being broken away, the top-lid of the cabinet body is removed and 65 I show four jackets that are held or clus-

tered together by means of a surrounding metal band or hoop 22, rivets 23 being used therefor, and, between the upper ends of said jackets and, also, between said upper ends of the jackets and the said band or hoop I provide or insert fillers or suitably shaped blocks of insulator material 24, the thickness of which corresponds to the width of the said band or hoop, and from the central filler-block I project downwardly a 75 rod or shaft 25 that practically constitutes a pillar duly incased within a tube or cylinder 26, the lower end of which pillar being inserted and held within a socketed block 27, as best seen in Fig. 2, and the lower end 80 of said pillar being passed on downwardly through a central opening made in the bottom of an upwardly-flanged pan or disk 28 that forms a turn-table from which the said jackets project upwardly in quadrant spaces 85 between four upright partitions 29 that project radially from the lower end of the said tube 26 in the said pan or disk 28 and thus stiffen or strengthen the pan bottom and provide chambers for the bottoms of the 90 respective jackets and their contained ice-cream cans.

The said lower end of the said vertical pillar 25 extends through a central opening in the upright box 30 of a horizontal plate 31 95 that is detachably-secured by means of bolts 32 to the upper face of the cabinet bottom, a square head 33 being provided at the said lower end to prevent the pillar turning and such angular head being otherwise 100 further clamped within the said upright box by the further turning home of the said bolts 32. At the upper end of the said pillar 25 I provide a cotter-pin 34 and a washer 35 to reliably and conveniently secure said 105 upper end in vertical position in the cabinet for the turn-table 28 and its supported jackets 21 that contain the ice-cream cans 20 for dispensing-service of their respective contents. The said upper end of the pillar 110 25 extends upwardly through an orifice made in the aforesaid central filler-block.

Thin blocks or plates 36 are provided on the inner faces of the upright walls of the cabinet to space the metal bands or hoops 22 115 at the top of the rotatory can-supporting device therefrom and at the same time provide a wear contacting surface to otherwise stabilize the said rotatory device in the cabinet and prevent its tilting or leaning.

The jackets 21 are suitably spaced from each other so that the chilled brine may circulate freely and uninterruptedly between them, and thereby maintain the same in uniformly freezing-cold condition entirely 125 around the jacketed cans, from top to bottom thereof.

Lids 37 and 38 are provided in the openings 16 and 17, respectively, of the top-cover 15 of the cabinet and arranged to slide hori- 130

zontally in grooves or ways 39 beneath the flat slab 40 on said top-cover 15, such slab being utilized to display or hold goods or things connected with the use of the cabinet 5 and, also, serving as a stop for limiting the rearward movement of the handles 41 on the said lids 37 and 38.

In Figs. 7 and 8, I show one of the lids in an open position and the other one closed, 10 which is the more common way of using the cabinet, but it is obvious that both lids can be slid into open position for the use of both chambers of the cabinet by more than one attendant simultaneously. These lids are 15 practically hidden or concealed from view, when opened for access to the chambers within, and there is a decided advantage in having these sliding-lids, as they are not lifted to and from place nor do they otherwise need any separate convenient place to 20 lay them down upon, as is commonly the practice with removable lids in general use. These lids are, further, preferably provided 25 with insulated, metal bottoms 42 that freely move in ways 39 on the underside of the wooden slabs that comprise them, and no sweating on the lower faces of these insulated bottoms 42 can, therefore, occur in the use of the cabinet. An insulated bottom 43 is 30 provided beneath the slab 40 and duly separated or spaced by the said ways 39, as best seen in Fig. 5. This insulated bottom 43 is likewise proof against sweating, especially when the lids are in their forward, closed 35 position.

Suitable, convenient can-lifting devices 44 are preferred in the several jackets 21, to facilitate the removal of the cans 20 when desired.

40 In use, the rotatory can-supporting device, in each chamber of the cabinet, makes it exceedingly possible and convenient to dispense the cream or other contents of the respective cans or containers from a single 45 point, which is located at the front next to the attendant, so that it saves him from uncomfortable and undue reaching toward the rear part of the cabinet to get at the contents of the cans, as in the old style of cabinets wherein a number of kinds of cream 50 are present for access in serving. In Figs. 4, 7 and 8 I have shown several cans at the front before the attendant, in convenient 55 position for him to serve equally well from either can and to include two kinds of cream, or a cream and a fruit-ice, as the case may be.

It will be seen, too, that a number of 60 patrons can be served with the same or a variety of ice-cream and other frozen products without the attendant or server moving or shifting away from the one point at the front through the use of the turn-table structure or rotatory carrier-device within the 65 cabinet. All of which is important, as it

saves time and the strength of the said server, and does not otherwise wear on the floor or the shoes.

The rotatory device herein can be easily turned around its upright rod or pillar 25 70 by inserting the tips of the fingers in the upper ends of the cans, or pressing on the skirting parts of the filler 24 and drawing or pushing forwardly in a circular path thereon, so as to bring either one or two of 75 the plurality of cans to the front for dispensing-service, or for replacing cans as may become necessary in replenishing the supply.

A man-hole 45 is provided in the front of 80 the cabinet for adjusted-connection with the electrical, mechanical, or other similar compressor means of refrigeration other than that of broken ice and the like in general use in service-cabinets. 85

It is obvious that, instead of a variety of ice-creams or fruit-ices being placed in the cabinet, the same kind of frozen product can be placed therein and part of the cans held back in storage or reserve, as it were, 90 ready to be turned into forward or front-point position for convenient dispensing or parcelling out in the ordinary service, especially when but one popular flavor is in demand or required, and that often happens. 95

It will be obvious, too, that uniform refrigeration to all the ice-cream containers is alike assured in the installation of a cabinet containing my rotatory turn-table can carrier-support within, wherever the ice-cream 100 or refrigerated product is served.

In using the cabinet, as herein shown and described, the brine-solution is placed in the main-receptacle so as to surround the jacketed-cans to a depth of a few inches below 105 the top thereof, and the act of rotating the turn-table carrier-device with the said jacketed-cans thereon serves to agitate or move the said solution into well-mingled circulation and adapted to reach all parts of the 110 said jacketed-cans without entering the tops thereof and liability of the solution getting into the contents of said cans. There is no loose lids on the tops of the cans, nor on the top-cover 15 to become misplaced or in the 115 way of the attendant or others using the cabinet, and said top-cover can be readily removed for any desired purpose or for access to the interior of the cabinet.

An array of soda-fountain syrup pump 120 and container jars 46 is provided across the top of the rear edge of the cabinet in convenient position for accessory use in connection with the ice-cream cabinet service. This is simply an adjunctive feature and is very 125 useful in the use to which my improved cabinet is put.

I claim:

1. An ice-cream cabinet comprising, in combination, a main single-chambered re- 130

- ceptacle adapted to contain a mechanically-refrigerated liquid-brine solution or pool of suitable depth therein, a revolute base pan or tray pivotally mounted in the bottom of the said main pool receptacle, a plurality of upright suitably coupled hollow columns or pillars supported in the said revolute base pan or tray and adapted to form closed-bottom jacket inclosure-members for containing ice-cream freezer cans under horizontally-rotatable segregate control, and a cover-member provided on the said main pool receptacle and having one or more lid-controlled service access-openings therein.
2. In an ice-cream service or dispensing cabinet, the combination of a main liquid-brine container-chamber, a turn-table mounted within the said chamber and immersed almost full-depth therein, an upright central rod or shaft around which the said turn-table is adapted to rotate, a plurality of upright cylindrical members forming hollow jackets that are mounted in circular array on the said turn-table, a band encircling the upper ends of said jackets and secured thereto, filler-blocks closing the spaces lying between the upper ends of said jackets and said bands, a removable cover-member mounted on the liquid-brine container-chamber of the cabinet and having openings therein for access to the cream-containers and, also, to the interior of the said brine-filled chamber, and an inter-slidable lid for closing the said openings.

WILLIAM F. BEATTY.
